Designs

No 1,191.

A. Czykiel.

Design for a Trade Mark

Patented Jan'y. 24. 1860.

DIRECTIONS FOR USING.

First.—Wash your head with cold water, and rub it well with a towel until you produce a glow.

Second.—Apply the Tonic, and rub it well on your head, for ten minutes.

Third.—Repeat this each night and morning, without fail, and you will succeed in Restoring the Hair.

Dec. 1191

Naphthali Ezekiel, of Richmond, Va.
Letters Patent No. 1191. Dated Jan'y 24, 1860.

The schedule referred to in these Letters Patent and making part of the same.

To all to whom the Presents shall come:

Be it known that I, N. Ezekiel, of Richmond, in the County of Henrico, and State of Virginia, have invented or produced a new design for a trade mark.

My invention or production consists in a design for a trade mark, as represented in the accompanying print.

What I claim as my invention or production and desire to secure by Letters Patent is the accompanying design, to be used as a trade mark.
